INVENTOR.

Francis W. Dunmore

UNITED STATES PATENT OFFICE.

FRANCIS W. DUNMORE, OF WASHINGTON, DISTRICT OF COLUMBIA.

RADIO RECEIVING APPARATUS.

1,405,905.

Specification of Letters Patent. Patented Feb. 7, 1922.

Application filed February 4, 1921. Serial No. 442,528.

(FILED UNDER THE ACT OF MARCH 3, 1883, 22 STAT. L., 625.)

To all whom it may concern:

Be it known that I, FRANCIS WINKLEY DUNMORE, a citizen of the United States, residing at 1727 Columbia Road, Washington, District Columbia, have invented new and useful Improvements in Radio Receiving Apparatus, of which the following is a specification.

The invention described and claimed herein may be used by the Government of the United States or any of its officers or employees in prosecution of work for the United States, or by any other person in the United States, without the payment of any royalty thereon.

A receiving tube, when directly connected across the tuning condenser of a coil aerial or direction finder has a voltage impressed on the grid in two ways: (1) by virtue of the fact that the coil circuit with tuning condenser is in tune with the incoming wave, and (2) by virtue of the coil acting as a capacity area, one end being at or nearer ground potential than the other, as the filament battery is connected to one end of the coil, and the small grid to the other, thus giving through the battery a relatively large capacity to earth as compared to the very slight capacity to earth through the small grid. As the coil is rotated, the impressed voltage in case 1 varies in amplitude from zero to maximum, according to the sine law, and is the useful voltage for receiving, or direction finding work. The induced voltage in case 2 is detrimental, as its amplitude is constant regardless of the position of the coil with respect to the approaching wave, and thus it is present at the position of zero induced voltage in case 1, which distorts and obscures the working point of zero induced voltage of case 1. Induced voltages from motors, ignition systems, etc., come under case 2. My invention relates to a method of greatly reducing the effects of this electrical dissymmetry or so-called antenna or capacity effect to ground as mentioned in case 2 above, the object being to give a quieter, sharper, and less distorted minimum, thereby improving the operation of the coil as an interference preventer and its accuracy as a direction finder.

Fig. 1 represents the receiving circuit

showing the iron core coupling coil and method of winding same. Fig. 2 shows a modification in the method of winding this coil. Similar numerals refer to similar parts in the two figures. 1 is the direction finder coil or coil aerial. 2 is the tuning condenser connected across the ends of the coil. 3 is a balancing condenser or mesny compensator which may be used for balancing what little dissymmetry in capacity to earth is not taken care of by the coupling coil. 4 is a suitable primary coil wound in one or more sections as shown and connected across the coil and tuning condenser. This coil with condenser 2 is resonant well away from the working wave lengths. The coil 4 is wound on an iron core 5, consisting of iron laminations about .001 inch thick. A suitable secondary coil 6 is wound in one or more sections on the core between the primary sections as shown. No. 11, Fig. 2, is a modified method of winding this coil. 7 is a 3-electrode receiving tube. 8 is a switch whereby the iron core 5 may be grounded. 9 is a suitable amplifier and accompanying apparatus. 10 is a connection to ground or counterpoise. The core 5 serves a two-fold purpose. First, to couple the coil aerial to the detector and distribute the capacity effect more evenly to earth; and second, to partially bipath to earth through the core disturbing influences such as motor and ignition noises.

I claim:

1. A radio receiver comprising a coil antenna, a transformer having two windings, one winding being connected to the terminals of said coil antenna, the other winding being connected to the input circuit of a vacuum tube, each of said windings comprising a plurality of individual sections connected in series, the sections of the primary and secondary windings being alternately arranged.
2. The combination as set forth in claim 1 in which a condenser is also connected across the terminals of said coil antenna.
3. The combination as set forth in claim 1 in which the transformer has an iron core suitable for radio frequencies.
4. The combination as set forth in claim 3 in which the iron core is grounded.

5. The combination as set forth in claim 1 in which the vacuum tube has an electron emitting cathode connected to ground.
6. The combination as set forth in claim 5 3 in which the iron core is connected to an electron emitting cathode of said vacuum tube.
7. The combination as set forth in claim 6 10 in which the electron emitting cathode is connected to a capacity.
8. The combination as set forth in claim 2 15 in which the transformer has an iron core suitable for radio frequencies.
9. The combination as set forth in claim 8 15 in which the iron core is grounded.
10. The combination as set forth in claim 2 20 in which the vacuum tube has an electron emitting cathode connected to ground.
11. The combination as set forth in claim 8 25 in which the iron core is connected to an electron emitting cathode of said vacuum tube.
12. The combination as set forth in claim 11 30 in which said cathode is grounded.
13. The combination as set forth in claim 1 in which the sections are arranged in axial alignment, there being an odd number of 35 secondary sections, one terminal of the central secondary section being connected to an electron emitting cathode of said vacuum tube.
14. The combination as set forth in claim 13, in which the other terminal of the central secondary section is connected to one 35 terminal of the remaining secondary sections which are connected in series and which are arranged alternately on either side of the central secondary section and working from center toward the two axial

ends, the remaining terminal of the last 40 section being connected to the grid of the receiving vacuum tube.

15. The combination as set forth in claim 7, in which a tuning condenser is connected across the terminals of said coil antenna, 45 said tuning condenser being shunted by two variable capacitances connected in series, the electrical conductor connecting said two capacitances being connected to ground.

16. A radio receiver comprising a coil 50 antenna, a transformer having primary and secondary windings each comprising a plurality of individual sections connected in series, the primary and secondary winding being alternately arranged in axial alignment, said coil antenna being connected to said primary winding; a tuning condenser shunting said primary winding; said tuning condenser being shunted by two variable capacitances connected in series, the 60 electrical conductor connecting said two capacitances being connected to ground; said secondary winding having an odd number 65 of sections, one terminal of the central section being connected to an electron emitting cathode of a vacuum tube, said cathode being grounded, the other terminal of the central secondary section being connected to one terminal of the remaining secondary sections which are connected in series and which 70 are arranged alternately on either side of the central secondary section beginning at the center and working from center toward the two axial ends, the remaining terminal of the last section being connected to the 75 grid of the receiving vacuum tube.

FRANCIS W. DUNMORE.
